GUSTAV E. HAAR, OF ANACOSTIA, DISTRICT OF COLUMBIA, ASSIGNOR TO JOHN H. STEPHENS, OF VERNON, TEXAS.

PUMP.

1,172,022.

Specification of Letters Patent.

Patented Feb. 15, 1916.

Application filed May 27, 1911, Serial No. 629,763. Renewed January 14, 1916. Serial No. 72,182.

To all whom it may concern:

Be it known that I, GUSTAV E. HAAR, a citizen of the United States of America, residing at Anacostia, in the District of Columbia, have invented certain new and useful Improvements in Pumps, of which the following is a specification, reference being had therein to the accompanying drawing.

This invention relates to certain new and useful improvements in pumps, and more specifically to that type known as lift pumps designed for use in connection with deep oil wells, Artesian wells, and domestic purposes.

One of the difficulties encountered in the operation of many forms of lift pumps as heretofore constructed, is the refusal of the foot valve to operate or seat, due to the excessive pressure caused by the liquid rising toward the surface, and this is especially so in wells of great depth, thus rendering the pump ineffective in use.

The main object of my invention is to overcome this difficulty which I accomplish by a pump in which the piston acts as the valve, and in which pump a vacuum is created within the pump barrel on the down stroke of the piston, whereby the entrance of liquid into the pump barrel is materially facilitated.

Another object of my invention is to provide a pump having a retainer valve for retaining the liquid raised into the pump, and in which, the greater the depth of the well, the more effectively the retainer valve is held in position, this being due to the fact that the weight of the liquid above such valve will always be in excess of the liquid below it.

A further object of the invention is to provide a pump of this type which is extremely simple in its construction, and strong, durable, and comparatively inexpensive to manufacture.

With the above and other objects in view, the invention consists in the novel construction, combination and arrangement of parts to be hereinafter specifically described and then claimed, and in describing the invention in detail, reference will be had to the accompanying drawings forming a part of the specification and illustrating a preferred embodiment of the invention, without, however, intending to confine myself to the specific embodiment shown, as in practice, vari-

ous changes may be made in the details of construction without departing from the spirit of the invention or scope thereof as claimed.

In the drawings: Figure 1 is a central vertical sectional view of a lift pump constructed in accordance with my invention. Fig. 2 is a cross sectional view taken on the line 2—2 of Fig. 1, and, Fig. 3 is a similar view taken on the line 3—3 of Fig. 1.

To put my invention in practice, I provide a pump-barrel or working-cylinder 5 open at both ends and of suitable diameter and length as existing conditions may require.

Suitably secured as by threading to the upper end of said barrel or cylinder, is a shell formed in two sections or members, 6 and 7 respectively. The lower member 6 comprises an annular body portion having a depending interiorly-threaded flange 8 for

connection with the exteriorly-threaded upper end of the barrel or cylinder 5. This member 6 of the shell is also provided on its upper face, intermediate the marginal sides of the member, with an upwardly-extending annular exteriorly-threaded annular flange 9 which receives the interiorly-threaded lower portion of the upper member 7.

The lower member is also provided with a valve seat 10 which is engaged by the retainer valve 11 sleeved onto the piston-rod 12.

The retainer valve 11 has combined with it an extended bearing-sleeve 14 preferably somewhat enlarged at its upper end and provided with a valve seat 15 which is engaged by a valve 16 carried by the piston rod 12.

The sleeve 14 provides a relatively long bearing for the rod 12, and obviously, when this sleeve is provided, the valve seat 15 must be at the outer or upper end of the sleeve, though where the long bearing may not be required, as in comparatively shallow wells, the shortening of the sleeve, or the omission thereof and the formation of the valve seat close to or in the upper face of

the retainer valve 11, with a corresponding change in position of the valve 16 on the rod 12, will in no wise change the function or operation of the parts 15, 16.

The upper member 7 of the shell is substantially bell-shaped, and as stated is threaded onto the flange 9 of the lower member 6. On its inner face this member is provided with a plurality of lugs 17 which project inwardly of the shell a sufficient dis-

tance to lie in the path of movement of the retainer valve 11 and thus constitute stops which act to limit the upward movement of said valve.

5 18 designates the well tubing or discharge pipe, which, it will be understood is, where the depth of the well requires it, formed of a plurality of connected sections of tubing, the lowermost of which has its lower end 10 threaded into the neck 7' of the upper member 7.

The piston 19, which also acts as the pump valve, comprises a hollow body having a closed lower end 20 to which the lower 15 end of the piston rod 12 is connected as by a threaded-connection as shown. The piston 19 is provided with one or more inlet openings 21, preferably four in this instance, which are equally spaced around the body. 20 On its upper end, the piston body is peripherally grooved to form an annular channel for the reception of a suitable packing 22, the grooving of the piston peripherally forming an annular upwardly-extending 25 flange 23 which is interiorly screw-threaded to receive a gland 24 angular in cross-section and the horizontal flange of which holds the packing within the groove provided therefor in the piston body.

30 In operation, assuming the parts are assembled, as above described, and the piston in the position shown in Fig. 1, it will be evident that the liquid in the well will enter through inlet openings 21 and rise in 35 the barrel or cylinder to the height of the liquid in the well, the pressure of the liquid raising the retainer valve 11 in case there be no liquid in the shell and well tubing. On the up-stroke of the piston, the closed 40 lower end thereof shuts off the flow of liquid through the inlet openings and into the barrel or cylinder as soon as said closed end enters the latter, the retainer valve being restrained by the stops 17 and the rod 12 45 moving upward through the sleeve 14. On the down stroke of the piston, the pressure of liquid above the retainer valve being greater than the pressure below it causes the valve to seat and as the piston moves down, 50 a vacuum is created in the barrel or cylinder below the retainer valve and above the piston. As soon as the closed end of the piston passes out of the barrel or cylinder, the ports 21 begin to uncover and the liquid in 55 the well rushes into the vacuous space above the piston, thus greatly facilitating the charging of the barrel or cylinder for the succeeding up-stroke of the piston. The valve 16 is provided so as to effectively prevent 60 leakage of the raised column of liquid that is above the retainer valve along the sleeve 14 and rod 12 when the piston is at the end of the down stroke or the pump inactive and the retainer valve seated. With this 65 construction it is to be observed that the

principle of the usual lift pump is reversed, a vacuum being created on the down-stroke of the piston so as to form a vacuous space above the piston, and the consequent aiding of a rapid inflow of liquid and effective filling of the cylinder upon the vacuum being broken.

In order that the pump may work equally well in deep wells, as in comparatively shallow wells, it is desirable that means be provided whereby fluid may enter the cylinder prior to the lower end of the inlet opening moving below the lower end of said cylinder, so that too great a vacuum may not be created during the latter part of the downward stroke of the piston, which would interfere with the easy operation of the pump. To this end, the piston in the embodiment of my invention herein shown is circumferentially reduced between its ends as clearly 85 illustrated in Fig. 1, and the inlet openings are made in this reduced portion, and are of less length than the width of such reduced portion, the upper and lower walls of the reduced portion, especially the lower 90 wall, being flared. As soon therefore, as the lower flared wall begins to uncover, liquid is permitted to enter the cylinder in small quantities, decreasing the vacuum and permitting the piston to complete its down 95 stroke with ease.

While I have described in detail a practical embodiment of the invention as practised by me, yet it will be evident that various changes may be made in the details of 100 construction without alteration of the spirit or scope of the invention.

What I claim is:

1. In a lift pump, a working cylinder, a piston rod, a piston thereon working in the 105 cylinder, a retainer valve sleeved on the rod, a valve seat on the sleeve of the retainer valve, and a valve on the rod to engage said seat.

2. In a lift pump, a pump cylinder, a shell connected to the upper end thereof and provided interiorly thereof with a valve seat, a retainer valve for engagement with said seat, a piston rod working through the retainer valve, a piston carried by the rod 110 and working in said cylinder, a valve carried by the piston rod above the retainer valve, and a valve seat surrounding the piston rod and engaged by said piston rod valve when the piston is at the end of its 115 down-stroke.

3. In a lift pump, a pump cylinder, a shell connected to the upper end thereof and provided interiorly with a valve seat, a retainer valve for engagement with said seat and 125 movable vertically in the shell under pressure of liquid above and below said valve, means carried by the shell for limiting the upward movement of said valve, a piston rod working through the retainer valve, a 130

5 piston carried by the rod and working in said cylinder, a valve on said rod above the retainer valve, and a valve seat surrounding the piston rod and engaged by said valve when the piston is at the end of its down-stroke in the cylinder.

4. In a lift pump, a pump cylinder, a shell connected to the upper end thereof, a tube or well casing connected to said shell, 10 a retainer valve movable vertically in said shell under the pressure of liquid above and below said valve and having combined with it a sleeve provided in its upper end with a valve seat, lugs carried by the interior wall 15 of the shell for limiting the upward movement of the retainer valve, a piston rod working through the retainer valve and carrying a valve to engage the valve seat on the retainer valve, and a piston on said rod 20 working in the cylinder and provided with inlets through which the liquid enters the cylinder, the ports in the piston being formed in a manner to permit the entry of fluid within said cylinder prior to the lower 25 end of the inlet port moving completely below the lower end of said cylinder.

5. In a lift pump, a pump cylinder, a

shell connected to the upper end thereof, a tube or well casing connected to said shell, a retainer valve movable vertically in said shell under the pressure of liquid above and below said valve and provided with a valve seat, lugs carried by the interior wall of the shell for limiting the upward movement of the retainer valve, a piston rod working 30 through the retainer valve and carrying a valve engaging the valve seat of the retainer valve, a piston on said rod working in the cylinder and provided with inlets through which the liquid enters the cylinder, and means for preventing leakage 35 along the piston rod of the liquid raised above the retainer valve, the ports in the piston being formed in a manner to permit the entry of fluid within said cylinder prior 40 to the lower end of the inlet port moving completely below the lower end of said cylinder.

In testimony whereof I affix my signature in the presence of two witnesses.

GUSTAV E. HAAR.
